Attorney

UNITED STATES PATENT OFFICE.

JOHN CALVIN SMITH, OF CHELSEA, MASSACHUSETTS.

DOORLOCK.

Application filed October 13, 1925. Serial No. 62,260.

This invention relates to improvements in closure fasteners, and is more particularly adapted to a lock for securing a door in a closed position.

Another important object of the invention is to provide a door lock which includes a horizontally swinging arm, the free end thereof being adapted to engage the inner face of the vertically swinging door, said arm being secured at its opposite end to a rotatable shaft vertically arranged in a suitable casing secured on the door frame, the casing being provided with a slot in which the intermediate portion of the arm is disposed whereby said arm is normally held in locked engagement with the door, there being further provided means for releasing the arm from the slot to facilitate the swinging movement of the arm out of engagement with the door to permit the latter to be unlocked and opened.

A further object is to provide a door lock of the above mentioned character, which is simple in construction, inexpensive, strong and durable and further well adapted to the purpose for which it is designed.

Other objects and advantages of the invention will become apparent during the course of the following description.

In the accompanying drawing forming a part of this application and in which like numerals designate like parts throughout the same:

Figure 1 is a view partly in elevation and partly in section of the door lock embodying my invention, showing the position of the locking arm when it is in engagement with the inner face of a door.

Figure 2 is a vertical sectional view through the casing, showing the arrangement of the vertical shaft therein, and

Figure 3 is a bottom plan view of the lock as attached to the door frame.

In the drawing, wherein for the purpose of illustration is shown the preferred embodiment of my invention, the numeral 1 designates a substantially rectangular shaped casing, the same including front and rear walls 2 and 3, respectively, the sides 4 and 5, and an upper end wall 6. The lower end of the casing is open as is clearly illustrated in the drawing, and the casing is adapted to be secured on the inner face of the door frame A, through the medium of the fastening screws 7 which extend through

the rear wall 3 of the casing. The side wall 4 of the casing is disposed adjacent the edge of the door frame, and the lower portion of the aforementioned side wall has a vertical slot 8 formed therein, the purpose of which will be hereinafter more fully described.

Arranged vertically within the lower portion of the casing, and adapted for rotation therein is the shaft or rod 9. Suitable guides 10 are arranged in the casing and cooperate with the shaft or rod 9 for supporting the same in its proper vertical position as is clearly illustrated in Figures 1 and 2. The lower end of this shaft or rod is provided with a transversely extending screw 11, and threaded therein is the reduced threaded end 12 of the laterally extending locking arm 13. This arm is substantially rectangular in cross section, and is adapted to be disposed normally within the slot 8 formed in the lower end of the inner side 4 of the casing 1, the free end of this arm extending transversely across the inner face of a vertically swinging door B. The free end of said arm is provided with an enlargement 14 which engages the inner face of the vertically swinging door, as clearly illustrated in Figure 3. When the arm 13 has been disposed within the slot 8, the door is held in a locked position against unauthorized opening and for the purpose of releasing the locking arm to permit the opening of the door, I have provided a highly novel and simple means, the construction of which will be presently described.

A head 15 is formed on the upper edge of the vertically arranged shaft or rod 9, the same being also substantially rectangular in design, and a notch 16 is formed in the inner side wall of said head, as clearly shown in Figure 1. Cooperating with the notch 16 is the latch 17, the same being of angular design, the horizontally disposed portion of said latch having its outer edge beveled as indicated at 18 for cooperation with the notch 16. The vertically disposed portion of said angular latch has its upper end reduced to provide a shoulder 19, and the purpose thereof will be presently apparent. The angular latch is adapted for slidable movement in a suitable guide 20 associated with the inner side wall 4 of the casing 1, as shown in Figure 1.

For the purpose of normally holding the

latch in locked engagement with the notched head 15 of the shaft or rod 9, whereby said rod or shaft is maintained in its uppermost vertical position in the casing, and to further dispose the locking arm 15 within the slot 8, I have provided a pawl 21, the same being pivoted intermediate its ends as at 22, the lower end of the pivoted pawl being adapted for engagement with the shoulder 19, or the reduced upper end of the vertically disposed portion of the angular latch. A coil spring 23 cooperates with the upper end of the pawl for maintaining the same in engagement with the upper portion of the angular latch.

A transversely extending shaft 24 is journaled at its respective ends in the front and rear walls 2 and 3 of the casing 1 adjacent the upper end thereof and secured on the intermediate portion of the shaft so as to be disposed within the casing is the segmental sleeve 25, the securing means therefor being illustrated at 26. Formed on the segmental sleeve 25 and depending therefrom is the lever 27, the lower end thereof being disposed laterally as illustrated at 28 and adapted to engage the outer base of the upper portion of the vertically disposed portion of the angular latches 17, as shown in Figure 1. A handle 29 is secured on the forward end of the shaft 24 for actuating the same.

With the parts arranged as shown in Figure 1 of the drawing, the arm 13 will be held in engagement with the inner face of the door B so as to prevent the opening of the latter. In order that the door may be opened, it is necessary that the arm 13 be swung out of engagement therewith and to accomplish this, the shaft 24 is rotated by actuating the handle 29. It is of course to be understood that, if desired, a key lock may be associated with the shaft for also effecting the rotation thereof. When the shaft rotates in one direction, the sleeve 25 which is secured on the shaft will be turned simultaneously therewith, and as a result the laterally disposed lower end 28 of the lever 27 which depends from the segmental sleeve will force the spring pressed latch 17 inwardly out of engagement with the notched head 15 formed on the upper end of the rod or vertical shaft 9, and as soon as the latch is out of engagement with the notched head 15, the coil spring 30 which encircles the vertical shaft and is secured at one end to said shaft and at its opposite end to the guide pin will force the vertical shaft downwardly. It is understood that when the latch 17 is in engagement with the notch 15 in the head 15, the coil spring will be placed under tension, and when the latch has been disengaged from the notched head, the spring will automatically expand to move the vertical shaft downwardly together with the arm 13 so as to disengage the arm from the

slot 8, and when said arm is out of engagement with the slot 8, the coil spring 30 will furthermore cause the shaft 9 and the arm 13 to rotate, whereby said arm is swung in a horizontal plane, and thereby disengaging the free end of the arm from engagement with the inner face of the vertically swinging door B. In this manner the lock is open, and the door may be easily and readily opened.

When the parts are reset or returned to the position shown in Figure 1, the arm 13 will hold the door in a closed position.

It will thus be seen from the foregoing description, that a highly novel and simple door securing means has been provided which may be readily and easily attached to the door frame, and will not in any way necessitate the alteration of either the frame or the door when installing the device.

While I have shown the preferred embodiment of my invention, it is to be understood that minor changes in the size, shape, and arrangement of parts may be resorted to without departing from the spirit of the invention, and the scope of the appended claims.

Having thus described the invention, what I claim as new is:—

1. A door lock comprising a casing adapted to be secured on a door frame adjacent the free edge of the door, the inner side of said casing having a slot formed in the lower portion thereof, a rotatable shaft arranged vertically in the casing and adapted for slidable movement therein, an arm secured to the lower end of the shaft and adapted for swinging movement therewith, said arm being normally disposed through the slot and having the free end thereof engaging the inner face of the door, means for locking the arm in this slot, and means for automatically disengaging the arm from the slot and effecting the swinging movement of the arm to an inoperative position when said aforementioned locking means is operated.

2. A door lock comprising a casing having its lower end open, said casing adapted to be secured on a door frame adjacent the free edge of the vertically swinging door, the side of the casing adjacent the edge of the door frame having a slot formed in the lower end portion thereof, a slidably and rotatable shaft arranged vertically within the casing, an arm secured to the lower end of said shaft and extending laterally therefrom, means cooperating with said shaft for securing the arm in said slot whereby the free end of the arm is held in engagement with the inner face of the door, and means associated with the shaft for automatically moving the same downwardly so as to disengage the arm from said slot and permit the swinging movement of said arm to an inoperative position when said locking means is released.

3. A door lock comprising a casing, the lower end thereof being open, said casing adapted to be secured on the frame for a vertically swinging door adjacent the edge thereof, the side of the casing adjacent said door edge having a slot formed in the lower portion thereof, a shaft arranged vertically within the casing and adapted for rotation and slidable movement therein, an arm secured to the lower end of said shaft and extending laterally therefrom, a latch cooperating with the upper end of the shaft for holding the same in its uppermost position whereby the arm is maintained in the slot so that the free end of said arm is held in engagement with the inner face of the door, and means associated with the shaft for automatically lowering the shaft and said arm to disengage the latter from said slot and to further permit the swinging movement of said arm to an inoperative position when said latch is released.
4. A door lock comprising a casing, the lower end thereof being open, said casing adapted to be secured on the frame for a vertically swinging door adjacent the edge thereof, the side of the casing adjacent said door edge having a slot formed in the lower portion thereof, a shaft arranged vertically within the casing and adapted for rotation and slidable movement therein, an arm secured to the lower end of said shaft and extending laterally therefrom, a latch cooperating with the upper end of the shaft for holding the same in its uppermost position whereby the arm is maintained in the slot so that the free end of said arm is held in engagement with the inner face of the door, and means associated with the shaft for automatically lowering the shaft and said arm to disengage the latter from said slot and to further permit swinging movement of said arm to an inoperative position when said latch is released, and means for disengaging the latch from engagement with the upper end of the shaft.
5. A door lock comprising a casing, the lower end thereof being open, said casing adapted to be secured on the frame for a vertically swinging door adjacent the edge thereof, the side of the casing adjacent said door edge having a slot formed in the lower portion thereof, a shaft arranged vertically within the casing and adapted for rotation and slidable movement therein, an arm secured to the lower end of the shaft and extending laterally therefrom, a notched head on the upper end of said shaft, a spring urged latch cooperating with the notch and head for holding the shaft in its uppermost position whereby the laterally extending arm is held in the slot in the side of the casing so that the free end of said arm is held in engagement with the inner face of the door, an expansible coil spring encircling said shaft, one end of said spring being secured to the shaft, the other end being secured within the casing, said coil spring being under tension when the door engaging arm is held in said slot and the latch is in engagement with the notched head of the shaft, and means for releasing said latch whereby the expansible coil will automatically lower the vertical shaft and said arm to disengage the latter from the slot to further permit the swinging movement of the arm to inoperative position.
6. A door lock comprising a casing, the lower end thereof being open, said casing adapted to be secured on the frame for a vertically swinging door adjacent the edge thereof, the side of the casing adjacent said door edge having a slot formed in the lower portion thereof, a shaft arranged vertically within the casing and adapted for rotation and slidable movement therein, an arm secured to the lower end of the shaft and extending laterally therefrom, a notched head on the upper end of said shaft, a spring urged latch cooperating with the notch and head for holding the shaft in its uppermost position whereby the laterally extending arm is held in the slot in the side of the casing so that the free end of said arm is held in engagement with the inner face of the door, an expansible coil spring encircling said shaft, one end of said spring being secured to the shaft, the other end being secured within the casing, said coil spring being under tension when the door engaging arm is held in said slot and the latch is in engagement with the notched head of the shaft, and means for releasing said latch whereby the expansible coil will automatically lower the vertical shaft and said arm to disengage the latter from the slot to further permit the swinging movement of the arm to inoperative position.
7. A door lock comprising a casing, the lower end thereof being open, said casing adapted to be secured on the frame for a vertically swinging door adjacent the edge thereof, the side of the casing adjacent said door edge having a slot formed in the lower portion thereof, a shaft arranged vertically within the casing and adapted for rotation and slidable movement therein, an arm secured to the lower end of the shaft and extending laterally therefrom, a notched head carried by the upper end of the shaft, a slideable latch arranged within the casing and cooperating with the notched head for holding the shaft in its uppermost position whereby the arm is maintained in the slot so that the free end of said arm is held in

engagement with the inner face of the door. a spring pressed pivoted pawl for holding the latch in locked engagement with the notched head, an expansible coil spring encircling the vertical shaft, one end thereof being secured to the shaft, the other end being secured to the casing, said coil spring being under tension when the shaft is locked in its uppermost position, said coil spring
10 adapted to automatically lower the shaft and said arm to disengage the latter from the slot and to further permit the swinging

movement of the arm to an inoperative position when the latch is released, and means for disengaging the latch from engagement 15 with the notched head, said means comprising a transverse shaft journaled for rotation in the upper portion of the casing, and a depending lever secured to the shaft and adapted to engage said slid able latch for moving 20 the same to an inoperative position.

In testimony whereof I affix my signature.

JOHN CALVIN SMITH.
